(57) **CLAIM**

The ornamental design for a combined liquid container and applicator, as shown and described.

DESCRIPTION

FIG. 1 is a top left perspective view of a combined liquid container and applicator in a closed position in accordance with the claimed design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a top left perspective view of a combined liquid container and applicator in an open position in accordance with the claimed design.

FIG. 9 is a front view of thereof.

FIG. 10 is a rear view thereof.

FIG. 11 is a left side view thereof.

FIG. 12 is a right side view thereof.

FIG. 13 is a top view thereof.

FIG. 14 is a bottom view thereof.

FIG. 15 is a top left perspective view of a combined liquid container and applicator in a closed position in accordance with the claimed design, wherein the break lines indicate indeterminate length.

FIG. 16 is a front view of thereof.

FIG. 17 is a rear view thereof.

FIG. 18 is a left side view thereof.

FIG. 19 is a right side view thereof.

FIG. 20 is a top view thereof; and,

FIG. 21 is a bottom view thereof.

The broken lines consisting of evenly spaced lines in the figures show portions of the combined liquid container and applicator that form no part of the claimed design. The break lines consisting of dashed dot lines that separate parts of the

(Continued)

combined liquid container and applicator represent indeterminate length and form no part of the claimed design.

1 Claim, 21 Drawing Sheets
